(57) **CLAIM**

The ornamental design for a camera mount, as shown and described.

DESCRIPTION

FIG. 1 is a lower, front, left perspective view of a camera mount of our new design;

FIG. 2 is a bottom plan view of the camera mount thereof; FIG. 3 is an upper plan view of the camera mount thereof; FIG. 4 is a front elevation view of the camera mount thereof; FIG. 5 is a rear elevation view of the camera mount thereof; FIG. 6 is a left elevation view of the camera mount thereof; and,

FIG. 7 is right elevation view of the camera mount thereof. Broken lines of equal length dashes (dash-dash) illustrate unclaimed portions of the camera mount. Broken lines of unequal length dashes (dash-dot) illustrate the bounds of the claimed design and form no part thereof.
